UNITED STATES PATENT OFFICE.

HARLIE EDWARD GREENE AND JOHN WILLIAM HALEY, OF HOT SPRINGS,
ARKANSAS.

FIRE-ALARM.

SPECIFICATION forming part of Letters Patent No. 623,009, dated April 11, 1899.

Application filed January 3, 1899. Serial No. 700,983. (No model.)

To all whom it may concern:

Be it known that we, HARLIE EDWARD GREENE and JOHN WILLIAM HALEY, of Hot Springs, in the county of Garland and State 5 of Arkansas, have invented a new and useful Improvement in Fire-Alarms, of which the following is a specification.

Our invention is in the nature of a fire-alarm box of that form in which the alarm is sent 10 in by the breaking of a glass plate and the manipulation of a push-button rendered accessible by the breaking of said plate instead of opening the box by a key. In the form of 15 box in which a key is first used to open the door it frequently happens that the box is rendered useless by an excited person putting in the key and turning it the wrong way or failing to put the key in deep enough before 20 trying to turn it, thus breaking the key and rendering the box useless before an alarm can be turned in.

Our invention consists in the peculiar construction and arrangement of a box employing such glass plate and push-button instead 25 of a key, as will be hereinafter described with reference to the drawings, in which—

Figure 1 is a front elevation of the box; Fig. 2, an interior view of the same with the door open and with the detachable cover removed from the interior case. Fig. 3 is a vertical longitudinal section taken on line 3 3 of Fig. 2. Fig. 4 is a section taken through the 30 clock mechanism or driving-gear on line 4 4 of Fig. 3. Fig. 5 represents sectional details 35 showing the manner of constructing the detachable glass-panel front of the interior casing.

In the drawings, A represents the outer box or metal casing, which is provided with a 40 hinged metal door A', having in the lower portion of the same a glass window, formed by rabbeting the inner edges of the opening in the door and fitting therein a thin frangible plate A², of glass, which is held in place by 45 lugs a and set-screws a' on the inside, which lugs are secured to the metal of the door-frame and have tapped through them the threaded ends of the set-screws a', which latter bear against the glass plate in such a way as to 50 allow the plate to be easily fractured by a blow from the outside.

Inside the outer case and in the lower part of the same directly opposite the frangible plate there is a push-button B, which when forcibly pushed in transmits its influence to 55 the operative mechanism of the box above, which operative mechanism is contained within a supplemental case C, contained within the outer case A and located immediately above the frangible panel in the outer case. 60 This supplemental case conforms in general shape to the upper portion of the outer case, and is a perfectly inclosed and tight inner case, its function being to protect the fine mechanism and contact-points of the fire- 65 alarm from the injurious effects of rain, snow, and dust when the frangible panel below is broken open. This supplemental case is screwed to the outer case by insulated screws a² and has a detachable front plate of heavy 70 glass C' contained within a marginal metal frame C². This plate and frame constitute a removable cover, which is tightly secured in front of the inner case, being removably secured thereto by a hole c in the top of the metal 75 frame, which fits over a stud c' on the top of the casing of the inner box, and by two set-screws c² c² at the bottom, which are tapped through the bottom of the metal frame and engage with the bottom of the inner casing. 80 In the face of the glass plate C' there is formed a hole c³, through which a winding-key is inserted to wind up the spring of the actuating mechanism from time to time. This hole is normally closed by a soft-rubber stopper or 85 plug.

The push-button B (see Fig. 3) has a shank portion that slides in a horizontal barrel B², whose end is flanged and screwed to the back of the outer case A. Within this barrel is a 90 helical spring B³, which tends always to press out the shank of the push-button. The top of the barrel and its flanged base are slotted longitudinally to permit the movement therein back and forth of a plate B', having an inclined 95 upper surface and fixed to and moving with the push-button. The push-button shank and inclined plate are introduced into the barrel through its slotted base before the barrel is secured to the casing A. A flanged screw-cap 100 B⁴ is afterward screwed onto the outer end of the barrel and the push-button then screwed

onto its shank. Immediately above the inclined plate B' there is a freely-sliding pin b, held vertically in guides fixed in the bottom of the inner casing C. This pin has a flanged head 5 to keep it from dropping through the guides, which guides consist of a flanged sleeve b', inserted in a hole in the bottom of the case C, the upper and exterior end of the sleeve being screw-threaded and provided with a nut b'', 10 which when screwed down clamps the bottom of the case C between it and the flange of the sleeve b', thus forming a closely-fitting rigid vertical guide, which gives passage-way to the pin b into the interior of the case C and 15 holds the pin vertical in its reciprocating movement. This forms the means by which the inward movement of the push-button is made to transmit the starting impulse through the case C to the mechanism within without 20 exposing the latter to the weather.

D (see Fig. 2) is an elbow-lever fulcrumed at its angle to a stud on the side of the inner case C, near its bottom, and having its lower arm resting directly above and adapted to be 25 raised by the lifting-pin b, extending down to the push-button. The other arm of this lever bears against a stud on the lower end of a lever E, also fulcrumed to a stud on the inner side of the case and having its lower end 30 pressed outwardly by a spring E'. The upper end of this lever E bears against still another lever F, which is fulcrumed upon the bridge-piece F' and has its lower end drawn toward the lever E by a helical spring F'', 35 anchored to a stud on the framework of the clock mechanism. The upper and short end of the lever F bears against the stop-lever G, which is pressed forwardly against the stop-wheel H by a spring G'. This stop-wheel H 40 is a simple disk, with a notch in it adapted to receive a stop-lug in the lever G. This stop-wheel is on a shaft with one of a train of gears operated by a coil-spring and which are held in check by the lug of stop-lever; 45 but when the stop-lever is raised it permits the gears to rotate at a uniform rate by reason of an escapement until the stop-wheel has made one complete revolution, when the lug of the stop-lever falls into the notch of 50 the stop-wheel again and arrests the further movement of the gears. From this description it will be perceived that when the push-button is forced in its effect is, through the pin b and the series of levers, to merely remove the stop from the clock mechanism and 55 allow the gears to operate.

I is the main winding-shaft, which carries outside the clock-frame a ratchet-wheel I' and detent I'', and inside the said frame (see Fig. 60 4) has the actuating coil-spring I³ and gear-wheel I³. This gear-wheel I³ meshes with a pinion J on the same shaft with a large gear-wheel J', and this gear-wheel J' meshes at one point on its periphery with a gear-wheel 65 K, that is on the commutator-shaft, and at another point actuates the train of gears L M, leading to the escapement N. This es-

capement is simply a vibrating pallet having weighted arms, whose weights are adjustable to or from the center by set-screws, so as to cause the escapement to move more or less rapidly, as may be required. When the stop 70 is removed from the actuating mechanism, it will be seen that the actuating-spring rotates the gears at a uniform rate of speed, and the 75 gears are so arranged as to rotate the commutator through two complete revolutions for each revolution of the stop-wheel, which gives the alarm and then repeats it, this being considered sufficient for all purposes and 80 involving the saving of much valuable time which a second repetition would involve.

O is the commutator-shaft, which bears inside the clock-frame (see Figs. 2 and 4) a plain metal disk o and on the outside of said 85 frame bears the commutator-wheel P, which has its periphery wrought into metal contacts representing the different stations. As shown, there are five contact-teeth, followed by three contact-teeth, representing the number "53." The number and grouping of these teeth are so arranged as to be different for each 90 fire-alarm box.

Q R are the two commutator-brushes. These are flat metal springs mounted on adjustable non-conducting blocks. Q presses 95 on the disk o and has its contact habitually closed, while R is only closed when it rests upon the tip of one of the teeth on the commutator-wheel. These teeth are in electrical 100 connection with the disk o through the shaft, and when brush R is resting on a tooth of the commutator-wheel the circuit is closed, and when it drops off one of these teeth it is 105 broken, thus sending signals to the fire department designating the location of the box from which the alarm was sent. The first tooth of the commutator-wheel is a broad one, and this is so arranged in relation to the stop-notch of the stop-wheel that when the 110 clock mechanism is stopped the brush R will always stand on this broad tooth, thus preserving the line-circuit closed through each instrument.

Below the clock mechanism there is located 115 on a non-conducting plate the three usual plates S T U, of which S and T are connected by binding-posts to the two line-terminals, while U is connected to the ground and has jagged edges to form a lightning-arrester. V 120 is a plug for connecting these plates at will.

W is a small metal insulated plate near plate S and adapted to be connected to it by the plug, and X is a permanently-closed key resting against said plate.

Y are the bell-magnets, and Z the bell.

The electrical connections for the various parts are as follows: Line-wire 1 enters the outer case of the box at the top, and passing down between the walls of the inner and outer 130 case enters the inner case at the bottom and connects with line-plate T, and from plate T a wire 2 leads to the commutator-brush R. From the other brush Q a wire 3 leads to plate

W, which is in electrical connection with key X. From the key X a wire 4 leads to the coils of the bell-magnet, and from the other pole of bell-magnet coils a wire 5 leads to line-plate S, and from S the wire 6 leads out through the bottom of the inner case, and thence through the top of the outer case to the aerial line again. From the plate U a wire 7 extends through the bottom of the box to the ground.

From this description it will be seen that the line-current normally passes through the commutator, the key X, and the bell-magnets, and when the glass panel is broken and an alarm is sounded by pushing in the push-button the line-current is made and broken a number of times corresponding to the number and arrangement of teeth on the commutator, which transmits the signal to the central station of the fire department. Furthermore, each time the circuit is made and broken in the box the bell within the box is rung, so that the sender of the alarm knows that the alarm-signal is going in all right to the central office.

The object of the key X in circuit is to enable any authorized person to communicate with the central office, and the object of the plate W with plug-socket and plug for connecting it to the line-plate S is to enable the circuit to be quickly re-formed in case the coils of the bell-magnet are destroyed and the circuit broken by a stroke of lightning or the crossing of the line-wires by a high-tension electric line. In such case if the fire-alarm circuit is disabled by the burning out of the coils of any one of the bell-magnets all that is necessary is to insert the conducting-plug V between plate W and plate S, so as to connect these, and this reestablishes the circuit of the instrument by cutting out the bell-magnets and making direct connection between the commutator-brush Q and the plate S.

One advantage of our box is its lower resistance, as it will not exceed twenty ohms, and by cutting out the bell-coils the resistance is of practically no consequence, and hence the line may be operated with very small battery-power.

Having thus described our invention, what we claim as new, and desire to secure by Letters Patent, is—

1. A fire-alarm box comprising an outer casing having a hinged front door with a frangible glass panel in the lower part of the same, a complete inner casing C with detachable front panel C' containing the operative mechanism and completely inclosing the same, said inner casing being located above the frangible glass panel of the door and with a space between its side walls and those of the outer case, a starting device for the operative mechanism, said starting device being located within the outer case opposite its frangible panel but outside of and below the inner case

to act upon the mechanism within, and three conducting-wires, two entering the outer case at the top, and one at the bottom, and all passing through the space between the inner 70 and outer case and entering the inner case at the bottom substantially as and for the purpose described.

2. In a fire-alarm box, the combination with the outer casing having a hinged door with a 75 frangible glass panel in the lower part thereof, a completely-closed inner casing located above the glass panel and containing the operative mechanism, a slotted barrel B² secured to the inner wall of the outer casing below the inner 80 casing, a push-button having a shank playing in the barrel and bearing a cam on its upper side with an inclined upper surface, a spring arranged in the barrel behind the push-button shank, a vertically-sliding pin 85 arranged in a tubular guide in the bottom of the inner casing, said pin being acted upon by the cam of the push-button below, and in turn acting upon the starting mechanism of the clock-gears within the inner case substantially as and for the purpose described. 90

3. The combination with the inner and outer cases; of the flanged and screw-threaded sleeve b' and nut b² clamping the wall of the inner case between them and forming an elongated passage-way therethrough, the headed pin b, and a spring-seated push-button bearing an inclined surface resting beneath the pin, said push-button having a range of movement at right angles to the pin substantially 100 as and for the purpose described.

4. In a fire-alarm box, the combination of the outer casing having a hinged door with a frangible glass panel in its lower portion, a complete inner casing containing the operative mechanism and located within the outer casing above the glass panel and with a space between its side walls and those of the outer casing, a starting device for the operative mechanism located below the inner casing 110 and opposite the frangible glass panel, means for connecting the starting device with the mechanism within the inner casing, and a marginal metal frame with glass panel and locking devices forming a removable tight 115 cover for closing in the front of the inner casing substantially as and for the purpose described.

5. In a fire-alarm box as described the combination with a push-button, and a sliding pin 120 passing through the bottom of the inner casing; of the spring-pressed levers D E and F, the stop-lever G, the notched stop-wheel H, the commutator-wheel P, the brushes Q, R, and the actuating coil-spring with gears and 125 escapement substantially as shown and described.
